Primary Examiner — Garth Rademaker*Assistant Examiner* — Llorellys Martinez-Rivera(74) *Attorney, Agent, or Firm* — Locke Lord LLP; Maria A. Scungio; David J. Silvia(57) **CLAIM**

The ornamental design for an expandable wire bracelet with crimp beads, as shown and described.

DESCRIPTION

FIG. 1 is a perspective view of the expandable wire bracelet with crimp beads, incorporating my new design.

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines in FIGS. 1-6 illustrate environmental subject matter and form no part of the claimed design.
